UNITED STATES PATENT OFFICE

HERBERT R. STRATFORD, OF CLEVELAND, OHIO, ASSIGNOR TO THE STRATMORE COMPANY, OF CLEVELAND, OHIO, A CORPORATION OF OHIO

SURFACING APPARATUS

Application filed July 29, 1927. Serial No. 209,193.

The present invention, relating as indicated to surfacing apparatus is more particularly directed to an improved surfacing or abrasive disk and to a means for supporting and removably retaining the disk while in operation. The principal object of the invention is the provision of a new and improved supporting pad having a certain compressibility and simple and convenient means for quickly securing thereto, or removing therefrom, a new and improved surfacing disk.

To the accomplishment of the foregoing and related ends, said invention, then, consists of the means hereinafter fully described and particularly pointed out in the claims; the annexed drawing and the following description setting forth in detail certain mechanism embodying the invention, such disclosed means constituting, however, but one of various mechanical forms in which the principle of the invention may be used.

In said annexed drawings:—

Fig. 1 is a bottom plan view of one form of my improved surfacing disk; Fig. 2 is a section of the same on the line 2—2 in Fig. 1; Fig. 3 is a central transverse section through my improved disk and supporting pad showing the engagement between the two; Fig. 4 is a view similar to Fig. 3, but on an enlarged scale and showing the engaging portions of disk and pad; Fig. 5 is a bottom plan view of another form of surfacing disk; and Fig. 6 is a partial section on an enlarged scale showing the engagement between the disk of Fig. 5 and complementary supporting pad.

Surfacing machines are now in quite general use for the surfacing, i. e., the abrading, polishing, etc., of metal, wood and other panels, in which the machine comprises a head or casing provided with handles for the use of an operator and having a suitable source of power either contained within the casing (as in the form of an electric or air motor), or transmitted through the casing by means of gears contained therein from a flexible shaft or other driving means. This type of machines includes an extending shaft on which there is ordinarily supported a supporting disk or pad, to which is removably

attached a surfacing disk, which may be either an abrasive disk or a polishing or rubbing pad, depending upon the nature of the work. It is very desirable from the standpoint of successful operation of the disk that it be relatively free from the supporting pad, although necessarily attached thereto at one or more points adjacent to the center, and it is equally desirable, in order to secure convenient and rapid removal and replacement of worn disks, that the latter be readily detached from the pad and a new disk positioned with equal convenience and quickness. The present invention is particularly directed to an improved means for securing the surfacing disk to the supporting pad, such means combining both the necessary freedom of movement between disk and pad, except at the point of attachment, and the convenience and speed of attachment and removal.

In Fig. 3 I have shown a typical type of pad consisting of lapped plates 4, 5, 6 and 7 of resilient material, such as rolled steel, upon the uppermost plate 5 of which is secured a compressible pad or disk 4. To the plate 7 is secured a hub 9 provided with a flange 8, the hub being adapted to be removably secured to the extending end of the driving shaft of the machine described above so that the entire assembly of compressible pad, supporting plates and hub are rotated through the rotation of the last-named member.

The pad 4 may be formed of various materials, any material being selected which has a sufficient compressibility to properly support the abrasive or other surfacing disk and allow a certain yielding in its supporting action. In Fig. 4 I have shown a pad as consisting of rubber and fabric vulcanized thereto, the layers of fabric 11 being spaced from each other and integrally united to the layers of rubber 10 by suitable vulcanization, while the upper layer 12 of fabric is provided with an inwardly extending tongue portion 13 free from the adjacent rubber 10 and capable of being inserted between a rebent collar 15 secured to a surfacing disk 16. The disk 16 may be formed of various materials, but is ordinarily a composite disk formed of layers of a suitable paper stock, to which is

adhesively united a fabric, while to the latter the grains of abrasive are also adhesively united on one surface. To the reverse side of the disk is secured a collar 15 provided with an outwardly extending flange 17 adapted to be inserted between the extending portion 13 of the fabric 12 and the adjacent layer of rubber 10. If necessary radial slits may be formed in the flange 17 to permit of its more convenient introduction between the element 13 and the pad 10 proper. After these elements have been engaged as described the pressure of the disk against the work and the unavoided friction between the contacting surfaces of the elements 15 and 13, 13 and 17, and 17 and 10 will provide a very secure driving engagement between disk and pad, and yet one which may be readily severed by merely pulling the disk away from the pad once the machine is stopped for the purpose of applying a new disk.

In Fig. 6 I have shown a pad provided with a plurality of inclined radially extending slots 20, which may be either separated slots 25 or may form part of a single encircling slot, into which are adapted to be inserted oppositely directed wings 21 secured to the lower surface of the abrasive disk 22. If the slots are separate slots, as shown in Fig. 5, there is of course a direct driving engagement between the radial end wall of each slot and the corresponding adjacent edge of the wings 21, while in the event of a continuous slot in the pad the friction between the side walls of 25 the wing and the slot is entirely sufficient for driving the disk in unison with the pad.

In either of the forms described above the disk may be readily inserted and instantly removed from the pad while the engagement 40 in two forms of the device is through relatively extensive frictional surfaces pressed into engagement by the pressure of the disk against the work and therefore graded according to the resistance to the driving, or it 45 is a direct driving engagement between wings on one element and cooperative slots or driving faces on the other. The entire device is simple, inexpensive and extremely convenient and rapid in operation.

50 Other modes of applying the principle of my invention may be employed instead of the one explained, change being made as regards the mechanism herein disclosed, provided the means stated by any of the following claims 55 or the equivalent of such stated means be employed.

I therefore particularly point out and distinctly claim as my invention:—

1. In apparatus of the character described, 60 the combination of a yieldable supporting pad provided with a projecting driving wing, and a surfacing disc provided with a driving surface positioned to be engaged by said wing whereby friction between said wing and driving surface due to the pressure of the disk

toward the pad serves to rigidly secure the same together.

2. In apparatus of the character described, 70 the combination of a yieldable supporting pad provided with a projecting driving wing on one surface, and a surfacing disc having a complementary driving surface positioned to be operatively engaged by said wing on said pad whereby friction between said wing and driving surface due to the pressure of the disk 75 toward the pad serves to rigidly secure the same together.

3. In apparatus of the character described, 80 the combination of a yieldable supporting pad provided with an annular frustro-conical driving wing on one surface, and a surfacing disc have a complementary pocket adapted to receive said wing in driving engagement, said disk when pressed toward said pad being adapted to rigidly lock the engaging surface 85 of said wing within said pocket.

Signed by me, this 27th day of July, 1927.
HERBERT R. STRATFORD.
